J. BECKER.
AMMONIUM SULFATE RECOVERY PROCESS.
APPLICATION FILED AUG. 12, 1918.

Patented Jan. 21, 1919.

1,291,730.

UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

AMMONIUM-SULFATE-RECOVERY PROCESS.

1,291,730.

Specification of Letters Patent. Patented Jan. 21, 1919.

Application filed August 12, 1918. Serial No. 249,380.

To all whom it may concern:

Be it known that I, JOSEPH BECKER, (assignor to H. Koppers Company, a corporation of Pennsylvania,) a subject of Germany, who has declared his intention of becoming a citizen of the United States, and is residing in Pittsburgh, in the county of Allegheny and State of Pennsylvania, have invented a new and useful Improvement in Ammonium-Sulfate-Recovery Processes, of which the following is a specification.

My invention relates primarily to the recovery of ammonia from coke-oven gas and has for an object the efficient combining of saturator and distillation processes with special economy of heat and simplification of operation; and the invention may also be applicable to the treatment of gas that is otherwise derived from the carbonization of coal, and may also have such other objects and results as are found to obtain in the processes hereinafter set forth and claimed.

In the accompanying drawings, Figure 1 is a conventional diagram illustrating an embodiment of the invention in a preferred arrangement of apparatus for practising its processes; and Fig. 2 is a key to the symbols employed in the various lines that show the connections between the apparatus indicated in Fig. 1.

The coke-oven gas from the ovens first enters and passes through the primary cooler 5. The condensate from such cooler is drained into the tar and ammonia-liquor tank 6, from which the ammonia-liquor is decanted into the ammonia-liquor tank 7. The cooled gas is drawn from the primary cooler 5 through the exhauster 8 and then forwarded into and through the tar extractor 9 in which the residue of the tar is extracted, and from which the recovered tar flows into the aforesaid tank 6. The ammonia-liquor is drawn from the said ammonia-liquor tank 7 by the pump 10 and forwarded to the elevated ammonia-liquor tank 11, from which it flows into the ammonia-still 12, to be there distilled by the heat from the steam supply 13. A portion of the cool gas from the tar-extractor 9 flows directly, through the pipe 14, into the saturator 15, but a portion is conveyed through the by-pass 16 to the still 12 and flows up through said still and issues therefrom with the still-vapors. Such still-vapors and gas issuing from the still pass first

through the dephlegmator 17 and then through the reheat 18 and thence are forwarded through the vapor-line 19 that leads back to the aforesaid gas connection 14 entering the saturator. Such heated inflow serves to heat the entire gas inflow into the saturator sufficiently to effect the evaporation required to precipitate the ammonium sulfate from the saturation-bath. The ammonia-free gas passes from the saturator 65 through the outlet gas-line 20. The dephlegmator 17 is supplied with cooling water circulating from its water inlet 21 to its water outlet 22. The condensate from the dephlegmator 17 flows back into the still 70 through the drain-line connection 23. The reheat is heated by steam supplied through the steam connection 24; and the steam from the reheat is led off through the pipe 25 that terminates in an injector nozzle within 75 the discharge end of the by-pass 16, to force the gas from said by-pass into the still and to serve as a supplemental steam-supply for the still, such steam-flow being adjusted by a valve in said pipe 25. The waste-drain 80 from the still is indicated at 26.

The gas intermixed and heated with the still-vapors provides a sufficient volume to carry, with the still-vapors, the heat required to be introduced into the cool gas 85 passing directly from the tar-extractor into the saturator, to save the reheating of the latter main volume of gas intermediate the tar-extractor and saturator, and substantial economy of heat is effected. 90

The processes of the invention may be practised in various ways, other than the particular embodiment that has been described for purposes of illustration, and still be within the scope and subject matter of the 95 claims hereinafter made.

I claim:

1. In a process for the recovery of ammonium sulfate, the combination of steps that consists in: cooling the ammonia-charged gas and draining off the condensate tar and ammonia-liquor; extracting the residue of tar from such cooled gas; distilling the ammonia-liquor; employing a portion of the cool tar-free gas to augment the volume of the vapors in the distillation operation and to derive heat from that operation; conducting the commingled distillate vapors and reheated gas into the current of the other portion of the cool tar- 100 105 110

freed gas, to impart heat to the latter; and passing the resultant superheated mixture of gas and still-vapors through a saturation-bath, to give up their ammonia in such bath 5 and to effect the deposition of ammonium sulfate therein; substantially as specified.

2. In a process for the recovery of ammonium sulfate, the combination of steps that consists in: cooling the ammonia-charged gas and draining off the condensate 10 tar and ammonia-liquor; extracting the residue of tar from the cooled gas; distilling the ammonia-liquor and dephlegmating and reheating the still-vapors; passing a 15 portion of the cooled tar-free gas into the current of the distillation, to augment the volume of the still-vapors and derive heat with them in the distillation and reheating operation; conducting the commingled volume 20 of superheated still-vapors and gas into the current of the other portion of the cool tar-free gas, to superheat the latter; and passing the resultant superheated mixture of gas and vapors into and through a saturation-bath, to effect absorption of their 25 ammonia and deposition of ammonium sulfate; substantially as specified.

3. In a process for the recovery of ammonium sulfate, the combination of steps 30 that consists in: distilling the condensate ammonia-liquor from cooled and tar-free

ammonia-charged gas; reheating a portion of said gas in the distillation operation; and employing the commingled hot gas and still-vapors to effect the superheating of the other 35 portion of the cool tar-free gas, so that the entire volume of gas and vapors, in passing through a saturation-bath for the absorption of their ammonia, effect the evaporation requisite to cause the deposition of ammonium 40 sulfate in said bath; substantially as specified.

4. In a process for the recovery of ammonium sulfate, the combination of steps 45 that consists in: distilling the condensate ammonia-liquor from cooled and tar-free ammonia-charged gas; reheating a portion of said gas in the distillation operation; conducting the other portion of the cooled gas into a saturation-bath; and employing 50 the commingled reheated gas and still-vapors to effect, in passing through the same saturation-bath, the evaporation requisite to cause the deposition of ammonium sulfate 55 in said bath; substantially as specified.

In testimony whereof, I hereunto set my hand in the presence of two subscribing witnesses.

JOSEPH BECKER.
